(57) **CLAIM**

The ornamental design for a horizontal bifold cell phone wallet, as shown and described.

DESCRIPTION

FIG. 1 is a perspective view in a closed position;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof;

FIG. 7 is a bottom plan view thereof;

FIG. 8 is a perspective view in an opened position;

FIG. 9 is a front elevational view thereof;

FIG. 10 is a rear elevational view in the opened position;

FIG. 11 is a side elevational view in the opened position;

FIG. 12 is an opposite side elevational view thereof;

FIG. 13 is a top plan view in the opened position; and,

FIG. 14 is a bottom plan view thereof.

The broken lines showing portions of the cell phone wallet are for purposes of illustrating environment and forms no part of the claimed design.

1 Claim, 10 Drawing Sheets
